UNITED STATES PATENT OFFICE.

WILLOUGHBY J. STARN, OF LAWNDALE, OHIO, ASSIGNOR OF ONE-HALF TO EDGAR L. JACOBS, OF LAWNDALE, OHIO.

WINDOW-CLEANING DEVICE.

1,083,842.

Specification of Letters Patent.

Patented Jan. 6, 1914.

Application filed July 29, 1913. Serial No. 731,879.

To all whom it may concern:

Be it known that I, WILLOUGHBY J. STARN, a citizen of the United States, residing at Lawndale, in the county of Summit and State of Ohio, have invented a new and useful Window-Cleaning Device, of which the following is a specification.

The present invention appertains generally to a window cleaning device, and aims to provide a novel and improved appliance of that character.

It is the object of the present invention to provide a novel and practical structure whereby a window pane may be cleaned or wiped on the outside, from the interior or inside.

Another object of the present invention is to provide a device of the nature indicated which shall be simple, durable and inexpensive in construction, which shall not be cumbersome so as to obstruct the vision through the window pane when the device is out of use, and which shall be practical, simple and efficient in its use.

A further object of the present invention is to provide a device of the character specified embodying a cleaning or squeegee element adapted to be moved over the surface of the window pane, in connection with means for maintaining the said element in co-operative relation with the window pane, and for properly actuating the same.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a front or exterior view of the device as applied to a window sash. Fig. 2 is a vertical sectional view taken on the line 2-2 of Fig. 1. Fig. 3 is a horizontal section taken on the line 3-3 of Fig. 1.

In the drawing, there has been illustrated an arbitrary window sash 1 containing a pane of glass, as usual. The window sash

1 may represent the motorman's window of a street car, the engineer's window of a railway locomotive, the pilot's window of a river or lake boat or steamer, the watchman's or switchman's window of a watch or switch tower, or in fact any other window of that character, it being observed that the present device has a large scope or latitude of application in practice. The present device may also be employed in connection with the wind shield of an automobile, if desired.

The present apparatus, as above intimated, is designed for the purpose of cleaning rain, snow, dust or other extraneous matter from the outer side or face of the window pane, in order to permit of clear vision through the pane.

In carrying out the present invention there are provided a pair of guides 2, which are preferably formed from suitable metallic rods and which are disposed in a horizontal manner along the outer sides or faces of the rails of the window sash 1. The ends of the guide rods 2 are bent angularly and are passed slidably through the sash at the joints or corner portions between the stiles and rails, the ends or extremities of the guide rods extending beyond the inner side or face of the sash. Wing nuts 3 are threaded onto the ends of the guide rods 2 and are spaced from the inner face of the sash, and coiled wire springs 4 are disposed around the ends of the guide rods between the nuts or adjustable members 3 and the inner face of the sash, washers 5 being preferably interposed between the springs 4 and the sash. The springs 4 are normally under compression, so as to yieldingly force the guide rods 2 inwardly, or in order to force the body portions of the guide rods toward the outer face of the sash.

The cleaning member, which is disposed on the exterior or outer side of the window pane, embodies the elongated clamping plates or strips 6, disposed vertically between the guide rods 2, and having their ends offset away from each other as at 7, and loosely embracing the respective guide rods. The inner edges 8 of the plates or strips 6 are offset or extended toward the window pane, between the stiles of the sash, while the outer edges of the plates or strips 6 are provided with the oppositely projecting flanges 9. A rubber strip 10 is sand-

wiched between the plates 6 and has its inner edge protruding slightly beyond the inner edges 8 of the plates 6, the rubber strip 10 serving as a wiper or squeegee, which 5 contacts with the window pane to swab or clean the same. Clamping screws 11 are engaged through the plates or strips 6 to clamp them together over the wiper or squeegee strip 10. It is to be noted that the 10 offset ends 7 which are provided with openings through which the guide rods 2 pass, serve to guide the cleaning member properly in a horizontal direction along the front of the window pane. The flanges 9 brace the 15 plate or strips 6 against flexing horizontally at their intermediate portions, as will be apparent. It is of course understood that the plates 6 may be separated for permitting the adjustment or replacement of the rubber strip 10, whenever desired or necessary.

Two pairs of brackets 12 are secured to each face of the sash, preferably to the stiles thereof, adjoining the angular ends of the guide rods, and a sheave 13 is journaled 25 within each bracket 12, the brackets on the inside and outside being opposed to each other. A pair of wire cables or flexible elements 14 are trained over the respective sets of pulleys or rotary guides, and the upper and lower runs of the cables 14 pass loosely through openings or apertures provided in the stiles of the sash. The horizontal runs of the cables or flexible elements 14 extend over the outer and inner sides of 30 the window pane, adjoining the stiles, the outer runs of the cables 14 being secured to the clamping strips or plates 6.

A vertical bar 15 is disposed upon the interior of the sash, and is secured at its terminals to the inner runs of the cables 14. The bar or handle 15 is so disposed, that when the cleaning member is at one end of its stroke, the bar or handle 15 will be at the other end of its stroke, in order that the 45 vision through the window pane will not be obstructed when the device is out of use.

It is to be observed that the wiper or squeegee strip 10 will be brought yieldingly against the outer face or side of the window 50 pane under the tension of the springs 4, which will draw the guide rods inwardly. The person behind or in rear of the window, may conveniently clean or wipe the outer face of the window pane, at any time, by 55 simply shifting the handle or bar 15 horizontally, the operation being repeated, if necessary. The movement of the bar 15

will transmit an opposite movement to the cleaning member, in order to swab the outer face of the window pane, it being noted that 60 the strip 10 will serve to remove snow, rain, or other extraneous matter from the outer face of the window pane. The bar or handle 15 may be grasped at any suitable point, without the liability of the cleaning 65 member tilting or sliding unevenly, due to the offset ends 7 of the clamping plates embracing the guide rods, as above indicated.

The present device may be readily applied to various windows and provides a 70 simple and inexpensive attachment adapted to be permanently assembled with the sash. The other advantages and capabilities of the present device will be apparent from the foregoing taken in connection with the 75 drawing, and it is to be noted that the objects aimed at are carried out satisfactorily by the present invention.

Having thus described the invention, what is claimed as new is:—

1. In a device of the character described, a pair of guide rods adapted to be disposed on the exterior of a window sash, and having their ends bent angularly to pass slidably through the window sash, a cleaning 80 member slidably carried by the guide rods to coact with the exterior of the pane, means disposed upon the interior of the sash and operatively connected to the cleaning member for sliding the same, and yielding 85 means disposed between the inner side of the sash and each terminal of each guide rod.

2. In a device of the character described, a pair of guide rods adapted to be disposed 90 upon the exterior of a window sash and having angular ends adapted to pass slidably through the sash, a cleaning member slidably carried by the guide rods and adapted to engage the exterior of the window pane, 100 means disposed upon the interior of the sash and operatively connected to the cleaning member so as to actuate the same, adjustable members mounted on the extremities of the guide rods, and springs adapted 105 to be disposed between inner side of the sash and the said adjustable members.

In testimony that I claim the foregoing as my own, I have hereto affixed my signature in the presence of two witnesses.

WILLOUGHBY J. STARN.
